TRACTOR MOUNTED WINCH

Robert B. Magee, Findlay, Ohio, assignor to The Buckeye Traction Ditcher Company, Findlay, Ohio, a corporation of Ohio

Original application April 30, 1942, Serial No. 441,125. Divided and this application July 13, 1942, Serial No. 450,738

1 Claim. (Cl. 254—166)

This invention relates to power control units or winches particularly for mounting on earth working tractors for actuating the scraper blades of bulldozers and trailbuilders.

An object is to provide a power control unit of the above character with a new and improved drive which enables the unit to be operatively connected to a power shaft of the tractor engine easily and without substantial change in structure of the tractor thereby facilitating assembly operations and reducing the cost.

Other objects and advantages will hereinafter appear and for purposes of illustration but not of limitation, an embodiment of the invention is shown on the accompanying drawing in which

Figure 1 is a top plan view of a planetary type winch and driving connections therefor, the same being shown mounted on the front end of a tractor, so much of the latter being shown as to enable the invention to be understood; and

Figure 2 is an enlarged side elevation partly in section showing the winch and its operative driving connection with the tractor engine crank shaft.

Referring to the drawing, 15 designates a cross member of the frame of the usual crawler type tractor, such cross member being at the front end of the tractor frame and secured to the front of the cross member 16 is an upright plate 16 which is disposed slightly in front of and in the main, below the engine radiator indicated at R. It will be understood that the grille for the radiator R is arranged in front of the latter and bows outwardly therefrom. Fixed to one side of the plate 16 and secured to the front face thereof is a bracket piece 17 which has a curved front face 18 conforming in general to the configuration of the grille beneath which it is disposed. The bracket has a forwardly extending portion 19 and secured to the front outer end of the portion 19 is a plate 20 which provides a front face or wall for the winch housing. A bottom wall piece 22 is welded to the lower end of the plate 20 and the wall portion 22 curves downwardly and thence extends rearwardly to the upright mounting plate 16, these parts being secured together in any suitable manner, as by bolts (not shown).

Preferably secured as by welding to the rear face of the opposite end of the front plate 20 is a casting 24 which has an inner curved portion 25 which also conforms to the shape of the radiator grille and is disposed directly below the same. Rigid with the casting 24 and extending laterally therefrom in spaced relation are plates 26 and 27. Pivot pins 28 and 29 are suitably

connected at their opposite ends to the plates 26 and 27.

The power control unit or winch generally indicated at W is of the planetary gear type and is equipped with a cable drum 30, clutch drum 32 and brake drum 34. Engaging the clutch drum 32 is a clutch band 34 and embracing the brake drum 31 is a band 33. The detail construction of the winch forms no part of the present invention and a general description thereof is therefore considered sufficient. For more detail understanding of the construction and operation of the power control unit, reference is hereby made to my co-pending application Serial No. 420,174, filed November 24, 1941, and entitled "Power control unit."

Description of the mechanism for operating the bands 33 and 34 is not given because the same forms no part of the present invention but reference is made to the above co-pending application wherein adequate description of the structure and operation is set forth.

One important feature of the invention resides in the ease by which the power control unit W is operatively connected to the power shaft of the tractor. As shown, the driving shaft 47 for the winch W is mounted in an anti-friction bearing 48 carried by the upright mounting plate 16. On the rear side of the plate 16 is a gear casing 49 which is suitably bolted in place. Within the gear casing and fixed to the shaft 47 is a ring gear 50 with which a pinion 51 meshes. The pinion 51 is carried by a stub shaft 52, which is journaled in anti-friction bearings 53. Fixed to the stub shaft 52 is a coupling part 54 which has a splined connection with an elongate coupling part 55. The coupling part 55 has a flange 56 which is secured by bolts 57 to the fan pulley 58, the latter being fixed to the engine crank shaft 59. It will be understood that the crank shaft 59 is the main engine crank shaft for the tractor and the fan pulley 58 is the usual fan pulley mounted on the end of the engine crank shaft, such structure forming a part of the ordinary tractor.

The particular form of coupling connection can be varied as will be readily understood and if desired, a flexible coupling could be employed to advantage. It will be evident that the simplicity and ease by which the winch is operatively connected to the power shaft, in this instance the engine crank shaft 59, enables the connection to be established within a minimum period of time. It is further manifest that the operative driving connection is such that the number of

parts is reduced to a minimum, thereby reducing the cost of the installation as well as the upkeep and repair.

This application constitutes a division of my co-pending application Serial No. 441,125, filed April 30, 1942, entitled "Tractor mounted winch."

It is to be understood that numerous changes in details of construction, arrangement and operation may be effected without departing from the spirit of the invention especially as defined in 10 the appended claim.

What I claim is:

In a tractor having a motor crankshaft extending toward the front end thereof, a sleeve member secured to the front end of said crankshaft for rotation therewith, a cross member of the tractor frame below and in advance of the front end of the crankshaft and a winch having 15

a driving shaft parallel to and in advance of said crankshaft, a plate secured to said cross member and extending upwardly therefrom, an aperture through said plate and bearing means in said aperture supporting the rear end of said driving shaft, means extending forwardly from said plate for supporting the forward end of said driving shaft, a gear casing secured to the rear face of said plate, an internal ring gear secured to the rear end of said driving shaft within said gear casing, a pinion meshing with said ring gear and secured on a stub shaft extending rearwardly through bearing means in the wall of said gear casing, and a splined coupling between said stub shaft and said sleeve member on the crankshaft.

ROBERT B. MAGEE.
